UNITED STATES PATENT OFFICE.

PATRICK J. MADDEN, OF BINGHAMTON, NEW YORK.

RAILROAD-TIE.

1,121,264.

Specification of Letters Patent. Patented Dec. 15, 1914.

Application filed April 4, 1914. Serial No. 829,417.

To all whom it may concern:

Be it known that I, PATRICK J. MADDEN, a citizen of the United States, residing at Binghamton, in the county of Broome and 5 State of New York, have invented certain new and useful Improvements in Railroad-Ties, of which the following is a specification.

My invention relates to an improvement 10 in railroad ties and particularly that class of railroad or trackage using electricity or for electrical signal devices and connections or electrical attachments operating in connection therewith, and it has for its object 15 to construct such a railroad tie by utilizing parts of wooden ties already laid so as to economize in the use of wood for tie purposes and at the same time to give rigid and safe support for the rails.

Another purpose is economy in trackage 20 and to prevent the complete loss of partly used ties from which may be cut perfect and sound parts. It is for the purpose of utilizing these parts in connection with such 25 trackage that my device is used and so constructed as to form a combined tie and plate and while preventing the waste of timber at the same time permits the springy features 30 of wood and the strength of a metal tie and tie plate so as to effectually prevent the spreading of the rails.

With these objects in view my invention 35 consists of certain novel features of construction and arrangement of parts as will be hereinafter fully described and pointed out in the claim, reference being had to the accompanying drawings in which:

Figure 1 represents a side view of my device. Fig. 2 represents a plan view of my 40 device. Fig. 3 represents a side view of a modified part of my device. Fig. 4 represents a view in cross section of a fragmentary part of my device.

The same reference characters denote like 45 parts in each of the several figures of the drawing.

In carrying out my invention I have the wooden blocks or section of a tie A. Mounted on these I have the plates B. B each of 50 which plates has the up-turned end 2. 2. Between the ends 2. 2 I have mounted the insulating material C. Through the ends 2. 2 and the insulating material C, I have the nut bolts 3. 3. Around the nut bolts 3. 3 I 55 have the insulating bushing 4. 4 and by

means of the nut bolts, the up-turned ends 2. 2 of the plates B. B, are thus clamped together. In each opposite end of each of the plates B. B, I have the recess 5. 5 and at the base of the recess 5. 5, I have the up-turned 60 lugs 6. 6', the lug 6 being of hook shaped formation and the lug 6' being of vertical formation which lugs contact with the base of the rails 7. 7. Mounted in the plates B. B are the usual rail spikes 8. 8. 8, etc., passing 65 through openings in the plates, 9. 9. 9, etc. Beneath the blocks A. A, I have extending under said blocks the plate D and supporting the lower sides of said blocks A. A. From each end of D extends the upturned 70 lug 10. 10. Through plates D and B. B are passed the bolts 11. 11 on which are mounted the nuts 12. 12, there being mounted about said bolts the insulating bushing 13. 13.

In a modified form of my device I have 75 one section of plate B overlapping the other section of plate B as shown in Fig. 3 and between which overlapping parts I have the insulating strip E. Passing through said overlapping parts B. B and through the insulating strip E, I have the bolts 3. 3 surrounded by the insulating bushing 4. 4. Mounted on the end of plate D, I have the clamp 14. 14 by means of the nut bolts 15. 15 which clamps 14. 14 extend over the ends of 80 blocks A. A. Whether the ends of plates B. B overlap or whether the ends have the upturned lugs as shown in Fig. 2 yet when bolted together by means of the connecting bolts they form one continuous plate. 90

Having thus described my invention, what I claim as new and what I desire Letters Patent for is as follows:

In a railroad tie, alining supporting members of wood, a sectional perforated binder 95 plate formed of two sections, the opposite ends of which being perforated and turned up, mounted thereon, forming a binding connection between the members; each outer end of said plate having a recess therein; 100 projecting lugs projecting from the base of each of said recesses and beyond the upper surface of each plate; one lug projecting vertically at right angles, the other in hook shaped formation and each adapted 105 to engage the outer edge of the track rail; an under plate extending beneath and beyond the ends of said supporting members and having upturned ends; a clamp extending over said supporting members and 110

down upon the extended end of said supporting plate and contacting with the upturned ends of the supporting plate; between the ends of said sectional plate insulating material mounted on bolts extending through said upturned ends; also insulating material mounted on nut bolts extending through the perforations of the

upper and lower plates of said supporting members.

In testimony whereof I have affixed my signature in presence of two witnesses.

PATRICK J. MADDEN.

Witnesses:

E. A. JOYNER,
M. F. TERRY.
